Attest

Patented Sept. 1, 1925.

UNITED STATES PATENT OFFICE.

OGASAP HAROOTUNIAN, OF LOS ANGELES, CALIFORNIA.

SWIMMING DEVICE.

Application filed July 9, 1924. Serial No. 724,977.

To all whom it may concern:

Be it known that I, OGASAP HAROOTUNIAN, a citizen of Armenia, residing at Los Angeles, in the county of Los Angeles and State 5 of California, have invented new and useful Improvements in Swimming Devices, of which the following is a specification:

This invention relates to swimmers' devices.

10 An object of this invention is to provide a buoyant support for bathers.

Another object of this invention is to provide a buoyant support which will support a beginner or person learning to swim in the 15 proper position while in the water, that is, with the top of the swimmer's shoulders substantially even with the surface of the water and his legs somewhat below the surface of the water.

20 A further object of this invention is to provide a buoyant support which can be held beneath the bather without the use of straps or similar devices and which will permit the free movement of the bather's limbs.

25 With these and other objects in view which will be made manifest from the following detailed description and specifically pointed out in the appended claims, reference is had to the accompanying drawings 30 for an illustrative embodiment of the preferred form of the improved device, wherein:

Figure 1 is a plan view of the buoyant support,

35 Fig. 2 is a section taken substantially on the line 2—2 of Fig. 1, and

Fig. 3 is a view showing the improved support as applied to a bather.

Referring to the accompanying drawings, 40 in which similar reference characters designate similar parts, a pneumatic bag is formed of a pair of duplicate pieces 10 and 11, one superposed upon the other and stitched around their edges, as at 12. These 45 pieces are made of any material adapted to hold air or gas, such as rubberized fabric, oil cloth and the like, and are shaped to provide a neck 13. The bag is substantially T-shaped in form, and has oppositely 50 extending side wings 14 and 15, which side wings have pointed extremities 16 and 17 respectively and are slightly curved rearwardly, as shown in Fig. 1. The bag has a rearwardly extending 55 central portion 18 terminating in a flar-

ing extremity 19. Upon the opposite sides of the central portion 18 are formed a pair of opposite projections 20 and 21 which are arranged adjacent the side wings 14 and 15 and cooperate therewith to form a pair of recesses 22 and 23.

Air is admitted into the bag or expelled therefrom through the neck 13 in which is provided a suitable stopper 24 having a metallic pin or eye 25, which may receive a suitable cord 26 to permanently associate the stopper with the bag by securing one end of the cord 26 to the neck 13.

As shown in Fig. 3, the bag is placed beneath the bather and the side wings 14 and 15 are bent over the bather's back, the recesses 22 and 23 conforming with the contour of the bather's body. The central portion 18 rests beneath the trunk of the bather and the flaring extremity 19 is placed between his legs. In this manner it is seen that the side wings 14 and 15 tend to prevent the buoyant support from slipping rearwardly from beneath the bather, and that the flaring extension 19 prevents the support from slipping from beneath the bather in the opposite direction.

Although the device herein shown has been described as a means for supporting amateur swimmers, it is to be understood that I contemplate the use of the device as an article for amusement. It is seen that the flaring extremity 19 extends from between the bather's legs and projects above the surface of the water, as in Fig. 3. By 90 using the buoyant support in the surf, a breaker, upon approaching the bather from the rear, strikes the flaring extremity 19 first and serves to easily propel the bather toward the shore, so that the buoyant support may be used to equal advantage as a 95 surf board.

It is to be understood that various changes in the detail of construction may be made without departing from the spirit or scope 100 of the invention as defined by the appended claims.

I claim:

1. A bather's supporting device comprising a flexible, pneumatic bag, said bag having oppositely extending side wings adapted to be placed beneath the arms of the bather and a rearwardly extending central portion adapted to be positioned between the legs 110 of the bather.

2. A bather's supporting device comprising a pneumatic bag, said bag having a pair of oppositely extending side wings, said side wings being curved rearwardly, and an outwardly flaring rearwardly extending central portion.
3. A bather's supporting device comprising a pneumatic bag, said bag having a pair of oppositely extending side wings adapted to be bent over the back of the bather, and a rearwardly extending central portion adapted to be held between the legs of the bather.
4. A bather's supporting device comprising a pneumatic bag, said bag having a pair of oppositely extending side wings adapted to be bent over the back of the bather, a rearwardly extending central portion adapted to be held between the legs of the bather, and projections formed upon the opposite sides of said central portion adapted to co-

operate with said side wings to form recesses.

5. A bather's supporting device comprising a flexible, pneumatic bag, said bag having oppositely extending side wings adapted to be placed beneath the arms of the bather and a rearwardly extending central portion adapted to be positioned between the legs of the bather, and means for admitting and expelling a gas into and from said bag.

6. A bather's supporting device comprising a flexible, buoyant member having oppositely extending side wings adapted to be placed beneath the arms of the bather and a rearwardly extending central portion adapted to be placed between the legs of the bather.

In testimony whereof I have signed my name to this specification.

OGASAP HAROOTUNIAN.
